UNITED STATES PATENT OFFICE.

CLARENCE H. BERRY, OF ISLIP, NEW YORK, ASSIGNOR TO WESTERN ELECTRIC COMPANY, INCORPORATED, OF NEW YORK, N. Y., A CORPORATION OF NEW YORK.

TELEPHONE SYSTEM.

Application filed August 30, 1926. Serial No. 132,333.

This invention relates to automatic telephone exchange systems, and more particularly to the cooperation between selective switches employed in the establishment of 5 telephonic connections.

In telephone systems of the type employing central office senders for controlling the operation of selective switches and in which the control of one switch is placed under 10 relays at a preceding switch, it has been found desirable to advance the controlling sequence switch associated with the said preceding selective switch following the completion of certain functions at the succeeding 15 switch.

According to the present invention the sequence switch of such preceding switch is held in one position during selections by the succeeding switch, and is advanced under 20 the control of the succeeding switch following the completion of selections at said latter switch. More particularly, two relays are provided in the circuit of the first 25 switch, one to control the sender and one to control the sequence switch during the selective operations of the succeeding switch dependent on the succeeding selector. On the completion of connections these relays are simultaneously operated to advance the 30 sequence switch to position for further operation.

During the completion of a call to a subscriber's line, connections are completed to the incoming selector under the control of 35 a sender. In the incoming selector one of the above mentioned relays is operated in the fundamental circuit including the stepping relay of the sender and operates the other relay to advance the incoming selector sequence switch. The revertive impulses which control the setting of the switch hold 40 the first relay operated in the usual manner. Following the completion of incoming selections a circuit is prepared for the second relay which includes a front contact of the 45 first relay and extends to the tip conductor of the final selector. The first relay is again operated in the fundamental circuit and pulses sent back from the final selector over 50 the ring conductor to release the stepping relay of the sender in the usual manner and determine the setting of the final selector. Following the completion of these final 55 selections ground is simultaneously applied to the tip and ring conductors whereby both

relays are operated and the incoming selector sequence switch is advanced to send back the usual signal initiating talking selection and the dismissal of the sender.

In the drawings Fig. 1 shows in diagrammatic form a subscriber's line and switches for extending a connection to the incoming selector which is shown in detail. Fig. 2 shows a final selector controlled through the cooperation of the incoming selector, and 65 Fig. 3 is a diagram showing the combination of Figs. 1 and 2 for a complete disclosure of the structure of this invention.

Assuming that the subscriber at substation 101 desires to converse with a subscriber 70 at substation 280, he will remove his receiver from the switchhook. Line finder 102 will thereupon operate to find the line and extend it to a district selector 103 which is associated by any suitable means with a 75 sender 104. When the sender is ready to receive dialing pulses a tone will be returned to the substation 101, after which the subscriber will dial the number of the wanted subscriber. District selector 103 and office 80 selector 105 will be operated under the control of the sender to select an idle incoming selector. When the office selector has come to rest and the sender is advanced to position for controlling incoming selections, a 85 circuit is established from battery through the winding of relay 106, lower right contact of cam 107, upper left contact of cam 108, over the tip conductor of selectors 105 and 103, through the stepping relay of the 90 sender, back over the ring conductor of selectors 103 and 105, upper right and lower left contacts of cam 109 to ground. Relay 106 closes a circuit from battery through the right winding of relay 110, upper left 95 contact of cam 111, lower left contact of cam 112, front contact of relay 106 to ground at the lower right contact of cam 113. Relay 110 operates and locks in a fundamental circuit extending from battery, through its right winding, lower left contact of cam 115, right front contact of relay 110, upper 100 right contact of cam 111, lower left contact of cam 112, front contact of relay 106 to ground at the lower right contact of cam 113. Relay 110, in turn, closes a circuit from battery through the winding of sequence switch magnet 100, lower left contact of cam 114, left front contact of relay 110, upper 105 left contact of cam 113 to ground, advanc- 110

ing the sequence switch to position 2. With sequence switch 100 in position 2, the circuit of updrive magnet 116 is closed and the incoming selector advanced in a brush selecting operation. The circuit for magnet 116 extends from battery, through the winding of magnet 116, lower contact of cam 117, left front contact of relay 110, upper left contact of cam 113 to ground. As the selector moves upward brush 118 makes contact with commutator strip 119, intermittently closing a circuit from ground over the upper right contact of cam 124, brush 118, conducting segments of strip 119, upper left and lower right contacts of cam 107 to the winding of relay 106. This circuit holds relay 106 operated while it shunts and de-energizes the stepping relay of the sender in the usual manner to operate the counting relays. When the condition set up in the sender has been satisfied, the fundamental circuit is opened by the sender and relay 106 releases, in turn, releasing relay 110. The release of relay 110 opens the circuit of magnet 116 and brings the selector to rest in position to trip the proper brush set. It also closes a circuit from battery through the winding of sequence switch magnet 100, upper right and lower left contacts of cam 120, left back contact of relay 110 to ground at the upper left contact of cam 113, advancing sequence switch 100 to position 3.

In position 3 the fundamental circuit is reestablished by the sender, operating relay 106, which in turn, operates relay 110, advancing sequence switch 100 to position 4, and in position 4 reoperating the updrive magnet 116 to cause the group selecting operation of the switch. Trip magnet 121 is operated in a circuit extending to ground at the lower right contact of cam 124 throughout positions 3 to 5, inclusive, and is therefore operated at this time to cause the tripping of the selected set of brushes at the beginning of the group selecting movement. During this operation an intermittent circuit is completed from ground at the upper left contact of cam 113, left front contact of relay 110, upper right contact of cam 117, brush 122, commutator strip 123, right contacts of cam 107, to the winding of relay 106. This circuit releases the stepping relay of the sender as above described. When the sender is satisfied, relay 106 releases, in turn, releasing relay 110, bringing the selector to rest. However, a circuit is provided, from battery through the right winding of relay 110, upper left and lower right contacts of cam 125, and thence in parallel over the lower left and upper right contacts of cam 126, commutator strip 127, to brush 128, and over strip 119 to brush 118, extending from brushes 128 and 118 over the upper right contact of cam 117, left front contact of relay 110 to ground at the upper

left contact of cam 113, which serves to prevent the release of relay 110 and the stopping of the updrive until the brushes are properly centered. The release of relay 110 advances sequence switch 100 to position 5 over the same circuit that advanced the switch to position 3. 70

With the sequence switch 100 in position 5 a local circuit is closed for relay 110 extending from battery, through resistance 129, left winding of relay 110, lower left contact of cam 113 to ground. Relay 110 operates in this circuit and closes a circuit from battery, through its right winding, lower left contact of cam 115, right front contact of relay 110, upper right contact of cam 111, upper left contact of cam 112 to sleeve brush 132. If the final selector connected to the first set of terminals of the selected group is busy, ground will be connected to the sleeve terminal and relay 110 will be held operated in this circuit. The operation of relay 110 closes the previously traced circuit for sequence switch 100, advancing it to position 6, in which position the holding circuit of relay 110 to the sleeve brush 132 is maintained. 75 80 85 90 95

With the sequence switch 100 in position 6 the updrive magnet is again energized and the selector advanced in a trunk hunting movement. As soon as an idle trunk is found, the holding circuit of relay 110 is opened and that relay releases connecting ground over the lower contact of cam 133, right back contact of relay 110, upper right contact of cam 111, upper left contact of cam 112 to sleeve brush 132 to render the final selector busy to other incoming selectors. With relay 110 released, the previously traced circuit is closed over the left back contact thereof, advancing sequence switch 100 to position 8. As soon as sequence switch 100 reaches position 6 1/4, direct ground is connected over the upper left contact of cam 124 to sleeve brush 132 to hold the final selector busy. Commutator strip 127 functions at this time in the same manner as it did in group selection to center the brush set. 100 105 110 115

With sequence switch 100 in position 8 the fundamental circuit is reestablished to relay 106 and that relay operates. With relay 106 operated, a circuit is now closed from battery through the right winding of relay 110, upper left contact of cam 111, lower left contact of cam 112, front contact of relay 106, lower left contact of cam 134 to brush 130, tip conductor 201 of the selected final selector, left contacts of cam 202, resistance 203, right contact of cam 204, right winding of relay 205 to ground over the right contacts of cam 207. At the same time a circuit is closed in parallel with the right winding of relay 110 from battery through resistance 129 over the lower left contact of cam 111 120 125 130 135

to the circuit just traced. The effect of this circuit is to prevent the operation of relay 110 in series with relay 205, and to provide sufficient current to operate relay 205.

- 5 Relay 205 thereupon locks in a circuit which extends from the right winding of relay 205 over the left contacts of cam 206, right front contact of relay 205, left contact of cam 224, upper right contact of cam 225 to ground. The operation of relay 205 closes a circuit from battery through the winding of relay 208, lower left and upper right contacts of cam 210, left front contact of relay 205 to ground. Relay 208 locks in turn a 10 circuit through its winding over the left contacts of cam 209, right front contact of relay 208, upper contacts of cam 211, contact 212 of jack 213, sleeve conductor 214, brush 132, to ground at the upper left contact of cam 214. This locking circuit remains closed until sequence switch 200 leaves position 6. The operation of relay 208 at this time closes a circuit from battery through the winding of final selector sequence switch magnet 200, 25 lower contacts of cam 215, to ground at the left front contact of relay 208, advancing the sequence switch to position 2.

With sequence switch 200 in position 2, a circuit is closed for high speed updrive magnet 216 extending from battery through the winding of magnet 216, upper left contact of cam 217, upper right contact of cam 210, left front contact of relay 205 to ground. Under the control of magnet 216 the final 30 selector is driven upward in a brush selecting movement. As brush 221 passes over commutator strip 220, a circuit is intermittently closed from ground over the lower right contact of cam 222, brush 221, commutator strip 220, left contacts of cam 219, ring conductor 218, brush 131, upper left and lower right contacts of cam 139, upper left contact of cam 108, lower left contact of cam 107 to the winding of relay 106. This circuit serves to hold relay 106 operated and shunt the stepping relay of the sender in the usual manner. When the sender is satisfied, it releases relay 106 opening the circuit of relays 110 and 205, releasing relay 205. Relay 205 opens the circuit of magnet 216 and brings the selector brushes to rest in position to trip the desired set of brushes. With relay 205 released, a circuit is closed from battery through the winding of sequence switch 35 magnet 200, lower left contact of cam 223, to ground at the left back contact of relay 205, advancing the sequence switch 200 to position 3 operating trip magnet 226.

When the fundamental circuit is again 40 established by the sender, relay 106 operates, reclosing the circuit of relay 205. Relay 205 operates and locks, and advances sequence switch 200 to position 4, in a circuit extending over the upper contacts of cam 210 to ground at the left front contact of relay 205.

High speed magnet 216 is again operated and an intermittent circuit is completed for relay 106 over conductor 218, the lower left and upper right contacts of cam 219, commutator strip 227, brush 228 from ground, 45 the right contacts of cam 210 to ground at the left front contact of relay 205. Trip magnet 226 is operated in positions 3 to 5 of sequence switch 200, in a circuit from battery through its winding to ground at the lower 50 left contact of cam 222, so that when the selector is moved upward under the control of magnet 216 in its group hunting movement, the selected set of brushes is tripped. When the sender is satisfied, relay 106 releases, in turn releasing relay 205, 55 whereupon the updrive is stopped, and sequence switch 200 is advanced to position 5.

When the fundamental circuit is established for units selection with the final selector sequence switch in position 5, relays 106 and 205 are operated as before and relay 205 locked. The operation of relay 205 advances the sequence switch 200 to position 6 over cam 210 and left front contact of relay 205. 60 In position 6 the holding circuit for 208 is transferred to a circuit through cam 209 and cam 242, back contact of relay 237, and left front contact of relay 208 to ground. A circuit is completed from battery through the 65 winding of low speed updrive magnet 232, upper right contacts of cams 217 and 210 to ground at the left front contact of relay 205.

In position 6 the intermittent circuit connected to conductor 218 extends over the left 70 contacts of cam 219, commutator strip 220, brush 221, lower right contact of cam 222 to ground. When the sender is satisfied, relays 106 and 205 release, relay 205 stopping the upward movement of the final 75 selector and advancing the sequence switch 200 to position 7 over cam 223 and the left back contact of relay 205.

Sequence switch 200 is then immediately advanced from position 7 to position 9 in 80 a circuit extending from battery through the winding of magnet 200, upper left and lower right contacts of cam 210, lower right contact of cam 222 to ground.

When sequence switch 200 passes through 85 positions 6½ to 8 inclusive, a circuit is closed from ground through winding of relay 233, lower contacts of cam 211 to sleeve brush 234. If the called line is in normal condition, battery will be connected to the sleeve 90 terminal through the cut-off relay 236 of the subscriber's line, or if the line is busy, this relay will be shunted by ground through a resistance. Relay 233 will operate unless the sleeve conductor is open or is grounded 95 through a low resistance such as would occur if the sleeve were accidentally grounded. If either of these last two unnormal conditions exists, relay 233 would not operate, and the circuit for operating relay 205 which will be 100

traced hereinafter is open. When sequence switch 200 reaches position 9, relay 205 would then be deenergized and no circuit would be provided for advancing the sequence switch out of that position. An alarm is therefore operated over cam 253 after a measured interval. The release of the selector is brought about manually after such a condition.

10 When relay 233 operates, indicating that the called line is normal, and switch 200 reaches position $7\frac{1}{2}$, a circuit is closed from battery through the left winding of relay 205, upper contact of cam 229, right winding 15 of relay 205, the front contact of relay 233, upper contacts of cam 215, back contact of relay 237, left front contact of relay 208 to ground. It will be remembered that relay 208 was locked to the sleeve conductor 214 in 20 positions 1 to 6 of the sequence switch 200. When the sequence switch reached position 6, this holding circuit was transferred to the lower right contact of cam 242, back contact of relay 237 and ground at the left 25 front contact of relay 208, which holding circuit is effective until the sequence switch leaves position 10 or until relay 237 is operated. Relay 205 operates in the circuit above traced and locks in a circuit through its two windings, left contacts of cam 206, right front contact of relay 205, left contact of cam 224, upper right contact of cam 225 to ground, until the sequence switch leaves position $9\frac{3}{4}$.

35 From the time that relay 205 released with the sequence switch 200 in position 6 following units selection until the sequence switch leaves position $8\frac{1}{4}$ ground is connected to conductor 218 over the lower contacts of cam 219, right back contact of relay 205, upper left contact of cam 224, from the upper right contact of cam 225, and, as soon as position 7 is reached, ground is connected to conductor 218 over the lower contacts of cam 219 from 40 the upper right contact of cam 222. This circuit extends as previously traced to the winding of relay 106, operating that relay independently of the sender.

When the sequence switch 200 passes 50 through position $8+8\frac{1}{4}$ direct ground is connected to conductor 201 over the lower left and upper right contacts of cam 202, right contacts of cam 210, and the lower right contact of cam 222. It will be remembered that 55 the circuit of relay 110 extended to conductor 201, over the front contact of relay 106, but this relay 110 could not operate, due to the shunt around its winding, in series with the resistance of relay 205. However, the 60 current through relay 110, when connected to direct ground as above described is sufficient to operate this relay. The operation of relay 110 advances sequence switch 100 to position 9, in which position a signal is trans-

mitted to the sender as will be described here- 65 inafter.

With relay 205 operated, a circuit is closed as soon as sequence switch 200 reaches position 9, for advancing to position 10, extending from battery through the winding of 70 magnet 200, upper contacts of cam 210, left front contact of relay 205 to ground.

While the sequence switch 200 is moving through positions $8\frac{1}{2}$ to 10, a circuit is closed from sleeve brush 234, lower right and upper 75 left contacts of cam 211, right front contact of relay 208, right contact of cam 238, winding of relay 237, lower contact of cam 225 to ground.

If brush 234 is resting on the terminal of a 80 busy line in a group leading to a private branch exchange, battery will be connected to the terminal through a high resistance and ground will also be connected thereto through a low resistance. Relay 237 is marginal so that it will not operate through so high a resistance in parallel with the busy ground or in parallel with another P. B. X. test relay. In consequence, relay 208 remains operated in its previously traced locking circuit. Relay 205 also remains operated in position 10 in a circuit which extends as previously traced to the upper left contact of cam 206, and is completed in this position over the lower right contact of cam 206 90 to ground at the left front contact of relay 205. With relay 208 operated, the sequence switch remains in position 10 and a circuit 95 is completed from battery through the winding of low speed updrive magnet 232, upper right and lower left contacts of cam 217 to ground at the left front contact of relay 208.

When an idle line is encountered no 100 ground will be connected to the sleeve terminal and the current will be sufficient to operate relay 237. Relay 237 also operates through the lower resistances connected to the sleeve terminals of individual lines and last lines of P. B. X. groups whether busy or not. The operation of relay 237 opens the 105 holding circuit of relay 208 which in turn opens the circuit of magnet 232 bringing the selector to rest. An additional holding circuit for relay 208 exists at this time from 110 ground at the left front contact of relay 208, lower left contact of cam 217, lower right contact of cam 210, brush 240, commutator strip 239, upper right and lower left contacts of cam 209 to the winding of relay 208 which 115 insures that relay 208 will remain energized until the brush set is properly centered. The release of relay 208 also closes a circuit from battery through the winding of magnet 200, upper left contact of cam 223, to ground at 120 the left back contact of relay 208, advancing the sequence switch to position 12. As soon as relay 208 releases, ground is connected to sleeve brush 234, extending from ground at 125

the left front contact of relay 205, lower contacts of cam 206, right front contact of relay 205, left contact of cam 224, through resistance 246, upper contacts of cam 241, right 5 back contact of relay 208, upper left and lower right contacts of cam 211, to the sleeve brush 234, as a temporary busy condition.

While sequence switch 200 is passing from position 10 to position 10½ with sequence switch 100 at position 9, the holding circuit of relay 205 is extended from the upper left contact of cam 206, over the lower left contact of cam 206, right front contact of relay 205, left contact of cam 224 to resistance 246 15 and thence to the sleeve brush 234, as above traced. If the line on which the brushes are standing is busy, ground will be connected to the sleeve terminal from the equipment with which it is engaged and relay 205 20 will be held operated until the sequence switch leaves position 10½. A locking circuit for relay 205 would then be closed over the upper left and lower right contacts of cam 206 to ground at the left front contact 25 of relay 205 in position 11 and the two circuits overlap sufficiently to prevent the release of relay 205. The operations following connection with a busy line will be described later.

Assuming that the line is idle, as soon as the sequence switch leaves position 10, relay 205 will release and connect ground from the upper right contact of cam 222 over its right back contact, left contact of cam 224 through 35 resistance 246 to sleeve brush 234 over the path previously described to make the line busy.

When the sequence switch reaches position 12, with relay 205 released, relay 208 is 40 operated in a circuit through its winding, lower left contact of cam 209, upper right contact of cam 242, to ground at the left back contact of relay 205. Relay 208 in 45 operating closes a circuit from battery through the winding of sequence switch magnet 200, lower contacts of cam 215, left front contact of relay 208 to ground, advancing the sequence switch to the talking position 13.

As soon as the sequence switch 200 reaches 50 talking position 13, ground is connected over the upper right contact of cam 225, through resistance 246, the left contacts of cam 241, to the sleeve brush to hold it busy throughout conversation. Relay 208 when operated 55 in position 12, locks over the left contacts of cam 209, right front contact of relay 208, upper contacts of cam 211, contact 212 of jack 213, sleeve conductor 214, brush 132, to ground at the upper left contact of cam 124. 60 In talking position, tip conductor 201 is extended over the lower contacts of cam 202 to the tip brush 254 and the tip of the called line. The ring conductor 218 is extended over the upper contacts of cam 252 to ring 65 brush 255 and the ring of the called line.

In the meantime the advance of the incoming selector sequence switch 100 to position 9 has taken place at position 8 the sequence switch 200 as above described and the incoming selector has functioned as follows.

The advance of sequence switch 100 from position 8 opens the circuit of relay 110 and that relay releases. With sequence switch 100 in position 9, relay 106 is connected over the upper contacts of cam 109 to the ring 75 conductor, and ground is connected over the lower left contact of cam 107 and the upper left contact of cam 108 to the tip conductor, reversing the direction of current in the fundamental circuit, indicating to the sender 80 that selections have been completed and that the district selector may be advanced to talking position, following which operation the sender is released. Relay 106 operates in this circuit and closes the circuit through 85 the right winding of relay 110. Relay 110 operates and advances sequence switch 100 out of position 9. The circuit of relay 106 is maintained through position 10, in turn holding relay 110 operated, but as soon as 90 sequence switch 100 leaves position 10, relay 106 releases, in turn releasing relay 110 and bringing the sequence switch to rest in position 11.

In position 11, relay 135 is connected to 95 the incoming tip and ring conductors, the circuit being traceable from battery, through the right winding of relay 135, upper winding of retard coil 136, left contacts of cam 137, upper left winding of repeating coil 138, 100 upper right and lower left contacts of cam 139, over the tip conductor, through the polarized relay of the district selector (not shown), back to the ring conductor, through the lower left winding of repeating coil 138, 105 upper right and lower left contacts of cam 140, lower winding of retard coil 136, left winding of relay 135, upper right and lower left contacts of cam 141, back contact of relay 106, lower right contact of cam 113 to 110 ground. Relay 135 operates, closing the circuit through the right winding of relay 110. Relay 110 operates and closes the previously traced circuit for magnet 100 advancing the sequence switch to position 12. Relay 110 locks as before through its right 115 winding, making the advance from position 11 independent of the continued operation of relay 135 and releases in position 11.

The testing operations of the final selector 120 above described take place quickly and that selector will now be in talking position 13. Therefore, when sequence switch 100 is in positions 12 and 13 ringing current is connected over the left contact of cam 142, 125 through the winding of relay 143, right back contact of relay 110, right contacts of cam 149 to the ring brush 131, and it will be transmitted over the ring conductor 218 of the final selector, upper contacts of cam 130

252, brush 255, over the ring conductor to the called subscriber's substation, back over the tip conductor to brush 254, lower contacts of cam 202, conductor 201, brush 130, 5 lower right contact of cam 134 to ground. As soon as interrupter 145 closes its upper contact a circuit is completed from ground over the interrupter contact, lower left and upper right contacts of cam 111, right winding 10 of relay 110 to battery. Relay 110 operates and advances sequence switch 100 to position 13. Relay 110 releases in passing from position 12 to position 13.

In position 13, a circuit is prepared for 15 relay 110 through its left winding and the lower left contact of cam 113, but the operation of relay 110 is prevented by shunt around its left winding extending through resistance 129, lower right and upper left 20 contacts of cam 120, back contact of relay 143, left back contact of relay 110 to ground at the upper left contact of cam 113. This shunt is present in position 12 but is ineffective on the right winding of relay 110. 25 The closure of its lower contact by interrupter 145 completes a circuit over the upper left and lower right contacts of cam 146, lower left contact of cam 114, winding of sequence switch magnet 100 to battery, advancing the sequence switch to position 14. 30 In position 14 ringing current is connected through interrupter 147 and the right contact of cam 142, to the circuit previously traced. Ringing current tone is transmitted 35 to the calling subscriber by means of a circuit, extending from the ringing circuit just traced, through condenser 144, upper right contact of cam 115, winding of supervisory relay 148, lower right winding of repeating coil 138 to battery. The current in 40 the winding of the repeating coil is inductively transmitted to the calling subscriber's station informing him that ringing is taking place.

45 When the called subscriber answers, relay 143 operates removing the shunt around the winding of relay 110 and that relay operates, cutting off the ringing current and advancing sequence switch 100 to position 15. The operation of relay 110 temporarily supplies talking battery through position 14½ of the sequence switch to the called subscriber over the lower right winding of repeating coil 138, winding of supervisory 50 relay 148, upper right contact of cam 115, right front contact of relay 110, right contacts of cam 149, to the ring conductor, the tip conductor being grounded over the lower right contact of cam 134. When sequence 55 switch 100 leaves position 14½, relay 110 releases, opening these temporary circuits but circuits are closed in position 14¾ which overlap the temporary circuits sufficiently to prevent the release of relay 148. These 60 circuits remain closed through position 16

and may be traced as follows: from the outgoing ring conductor over the upper contact of cam 134 and the upper right winding of repeating coil 138 to ground and from the outgoing ring conductor over the upper contacts of cam 149, winding of relay 148 and the lower right winding of repeating coil 138 to battery, respectively, operating relay 148.

Sequence switch 100 is immediately advanced to position 16 in a circuit over the upper contacts of cam 112, upper left contact of cam 124 to ground. With sequence switch 100 in positions 14½ to 16, relay 110 is released. The circuits from the windings 75 of relay 135 in positions 15½ to 16 of sequence switch 100 to the tip and ring conductors of the incoming trunk circuit may be traced as follows: battery, through the right winding of relay 135, upper winding 80 of retard coil 136, upper left contact of cam 115, upper right and lower left contacts of cam 125, left back contact of relay 110, lower right and upper left contacts of cam 137 to the upper left winding of repeating 85 coil 138; from ground over the lower right contact of cam 113, back contact of relay 106, lower left and upper right contacts of cam 141, left winding of relay 135, lower winding of coil 136, upper right and lower 90 left contacts of cam 146, right back contact of relay 110, right contacts of cam 140 to the lower winding of repeating coil 138. These circuits supply battery and ground 95 to the district selector in the reverse direction from that previously traced, for the purpose of operating a supervisory signal, controlling coin collecting apparatus or any other desired operation.

100 As soon as switch 100 reaches position 16 relay 110 is reoperated in a circuit from battery through resistance 129, left winding of relay 110, front contact of relay 148, upper right contact of cam 108, lower left contact of cam 107 to ground. Sequence switch 100 remains in position 16 throughout conversation and relay 110 remains operated under the control of the called subscriber. With relay 110 operated the circuits of relay 135 are from battery through the right winding of relay 135, upper winding of coil 136, upper left contact of cam 115, right front contact of relay 110, right contacts of cam 140, lower left winding of repeat coil 138; from ground over the lower right contact 110 of cam 113, back contacts of relay 106, lower left and upper right contacts of cam 141, left winding of relay 135, lower winding of coil 136, left contact of cam 117, left front contact of relay 110, lower right and upper left contacts of cam 137, to the upper left winding of repeat coil 138 and over the calling line and to battery over the circuit 115 above traced.

120 When the calling subscriber restores his 130

receiver to the switchhook at the end of conversation, relay 135 will be released, closing a circuit from ground over its left back contact, lower left and upper right contacts 5 of cam 109, winding of relay 106 to battery. Relay 106 operates and closes a circuit from battery, through the winding of sequence switch magnet 100, upper left and lower right contacts of cam 112, front contact of 10 relay 106 to ground at the lower left contact of cam 113. In this circuit the sequence switch is advanced to position 18, as soon as the sequence switch leaves position 17, the circuit of relay 148 is opened, in turn 15 opening the circuit of relay 110, if these relays have not been released by the disconnection of the called party.

When the sequence switch arrives in position 18, a circuit is closed from battery, 20 winding of downdrive magnet 150, lower right contact of cam 108 to ground at the lower left contact of cam 107. The selector switch is restored to normal position under the control of the downdrive magnet 25 150. As soon as it reaches normal a circuit is closed from battery, through the winding of sequence switch magnet 100, lower right contact of cam 114, normal commutator segment 151, brush 128 to ground at the 30 upper right contact of cam 124, advancing the sequence switch to position 1. While the sequence switch remains in position 18, ground is connected to the tip and ring terminals appearing in the bank of the district or office selector, to prevent false operation 35 of the sender if this incoming selector is taken for use during its restoration. These circuits may be traced from the tip conductor over the upper left contact of 40 cam 108 to ground at the lower left contact 107 and from the ring conductor over the upper right and lower left contacts of cam 109 to ground.

When sequence switch 100 leaves position 45 17 $\frac{1}{4}$ ground is removed from sleeve brush 132, permitting relay 208 to release. The release of relay 208 advances sequence switch 200 to position 16 in a circuit from battery through the winding of magnet 200, upper left contact of cam 223, to ground at the left back contact of relay 208.

In positions 15 to 15 $\frac{1}{4}$ of sequence switch 200 a circuit is closed from battery through the left winding of relay 205, upper contact 55 of cam 229, right winding of relay 205, upper contacts of cam 207, back contact of relay 237, lower left contact of cam 217, lower right contact of cam 210, to ground at the lower right contact of cam 222. If the 60 called subscriber has not restored his receiver to the switchhook, relay 205 locks in a circuit extending through its two windings, as previously traced, left contacts of cam 206, right front contact of relay 205, 65 upper right contact of cam 224, over the

called subscriber's loop, back to the right contacts of cam 202; left front contact of relay 205 to ground. If the called subscriber still fails to hang up his receiver, interrupter 243 will close its upper contact, 70 after an interval, completing a circuit thereover, over the upper left contact of cam 242, and lower left contact of cam 209 through the winding of relay 208 to battery. Relay 208 operates and completes a circuit through 75 the winding of sequence switch magnet 200, upper left contact of cam 210, lower left contact of cam 217, to ground at the left front contact of relay 208 advancing the sequence switch to position 17, releasing relay 208. 80 After a predetermined interval, interrupter 243 closes its lower contact and extends a circuit thereover the left contact of cam 242 and thence as traced through the winding of relay 208. Relay 208 again advances the 85 sequence switch, this time to position 18, and releases. When the sequence switch leaves position 17, the holding circuit of relay 205 is opened and that relay releases.

If the called subscriber hangs up promptly 90 the locking circuit above described for relay 205 will be open and that relay will release in position 16. Sequence switch 200 is then advanced to position 18 in a circuit over the lower left contact of cam 223 to ground at 95 the left back contact of relay 205.

In position 18 a circuit is closed for down-drive magnet 244, extending over the lower right contacts of cams 217, 210 and 222 to ground. The selector switch is restored to 100 normal under the control of magnet 244, trip magnet 226 being operated. When the selector reaches its normal position, a circuit is closed from battery through the winding of sequence switch magnet 200, lower right contact of cam 223, normal commutator segment 245, brush 228 to ground at the lower right contact of cam 222, advancing the sequence switch to position 1.

The release of relay 208 when sequence 110 switch 100 leaves position 17 $\frac{1}{4}$ connects ground to sleeve conductor 214, from the lower contact of cam 225, through the winding of relay 237, lower left contact of cam 238, right back contact of relay 115 208, and the upper contacts of cam 211. This ground serves to mark the final selector busy to other incoming selectors. When sequence switch 200 arrives in position 16, ground over the left contact of cam 120 225 is substituted for ground through the winding of relay 237, continuing the busy indication until the selector is ready for reuse.

If the called line had been busy when 125 tested by relay 205 in positions 10 to 10 $\frac{1}{4}$ as above described, relay 205 would operate and lock as described and remain operated when the switch 200 reached position 12. With relay 205 operated, a circuit is 130

closed in position 12 through the winding of downdrive magnet 244, lower right contact of cam 217, upper right contact of cam 210 to ground at the left front contact of relay 205. The final selector is restored to normal under the control of magnet 244, the trip magnet 226 also being operated at this time. When the final selector reaches normal, a circuit is closed from battery through the winding of relay 208, lower contacts of cam 209, normal commutator segment 245, brush 228 to ground at the lower right contact of cam 222. The operation of relay 208 advances sequence switch 200 to position 13 as previously described. With the final selector switch normal a circuit is closed from battery through the winding of magnet 200, lower right contact of cam 223, normal segment 245, brush 228 to ground at the lower right contact of cam 222, advancing the sequence switch 200 to position 14.

When the sequence switch 200 leaves position 12, the holding circuit of relay 205 is opened and relay 205 releases. With relay 205 released and sequence switch 200 in position 14, a circuit is closed from ground through interrupter 247, lower left contact of cam 229, left winding of relay 205 to battery causing relay 205 to operate intermittently. On each operation of relay 205 a circuit is closed from ground through the secondary winding of tone coil 248, upper contact of cam 204, resistance 203, upper right and lower left contacts of cam 206, right front contact of relay 205, lower contact of cam 224, to ring conductor 218, and thence through relay 143 to the ringing source sequence switch 100 being at the time in position 12. Relay 143 operates, causing the advance of switch 100 from position 12 to talking position 16, in which position the tone is transmitted to the lower right winding of repeating coil 138 from whence it is inductively transmitted to the calling subscriber, indicating the fact that the line is busy. When the calling subscriber restores his receiver in response to this signal, sequence switch 100 is advanced from position 16 to position 18, releasing relay 208 and advancing sequence switch 200 to position 16, as previously described. Since the final selector is normal at this time, a circuit will be closed from battery through the sequence switch magnet 200, lower right contact of cam 223, normal segment 245, brush 228, to ground at the lower right contact of cam 222, advancing the sequence switch 200 to position 1 and restoring the final selector completely to normal.

If the final selector should fail to operate correctly and advance sequence 100 out of position 8 within a predetermined time, a circuit is closed by means of interrupter 157 extending from battery, through the right

winding of relay 135, retard coil 136, lower contact of interrupter 157, upper left contact of cam 133 to ground. The operation of relay 135 in this circuit closes a circuit for supervisory relay 148 extending from battery, through the lower right winding of repeating coil 138, winding of relay 148, left contacts of cam 149, front contact of relay 135, left contacts of cam 140, winding of retard coil 136, left winding of relay 135, right contacts of cam 141 to ground. This circuit serves to hold relay 135 operated as well as to operate relay 148. With relay 148 operated, as soon as interrupter 157 closes its upper contact, a circuit is completed from ground over the upper contact of cam 133, upper contact of interrupter 157, front contact of relay 148, left winding of relay 110, resistance 129 to battery. Relay 110 operates in this circuit and advances the sequence switch to position 9 as previously described. In positions 9 and 10 relay 106 is connected in the reverse direction to the incoming line as described, operating relay 110 and advancing the sequence switch to position 11. Relay 135 is connected to the incoming line and operates relay 110 as before, advancing the sequence switch to position 12. The advance to position 14 is the same as previously described by operation of interrupter 145 and operation of relay 110. The sender responds to the premature reverse battery signal to cause the district selector to connect a tone to the calling line to indicate that the call could not be completed. When the calling subscriber restores his receiver in response to this tone, relay 135 releases, operating relay 106 which closes the circuit of relay 110 and thus advances switch 100 to position 15. Switch 100 is then advanced to position 16 over upper right and lower left contacts of cam 122, left front contact of relay 106 to ground at cam 115. Since relay 148 is not operated when the sequence switch arrives in position 16, relay 110 is not operated and the selector proceeds to restore as above described.

Although the present invention has been disclosed in connection with panel type switches it may be applied to other kinds of switches.

What is claimed is:

1. In a telephone system, a called line, selector switches for extending a connection to said line, a sender for controlling said switches, a plurality of control circuits extending between said switches, means in one of said switches under control of said sender for controlling the selecting functions of a succeeding switch, means in said first switch for controlling said sender, and means at said second stage for simultaneously establishing said control circuits to control said last means.
2. In a telephone system, a called line,

- selector switches for extending a connection to said line, a sender for controlling said switches, a plurality of control circuits extending between said switches, a pair of relays in one of said switches, one of said relays controlled by said sender to control the selecting functions of a succeeding switch, and means in said first switch for controlling said sender, said means controllable by the simultaneous operation of both said relays over said control circuits.
3. In a telephone system, a called line, selector switches for extending a connection to said line, a sender for controlling said switches, a plurality of control circuits extending between said switches, a pair of relays in one of said switches, a fundamental circuit connecting said sender with one of said relays, means for operating said relay to control the selecting functions of a succeeding switch, means in said first switch to reverse the connection of said relay to said fundamental circuit to control said sender, and means for rendering said reversing means effective controlled by the simultaneous operation of both said relays over said control circuits established by said second switch.
4. In a telephone system, a called line, selector switches for extending a connection to said line, a sender for controlling said switches, a plurality of control circuits extending between said switches, means in one of said switches under control of said sender for controlling the selecting functions of a succeeding switch, means in said first switch for controlling said sender, said means controllable from said second switch over said control circuits simultaneously established at said second switch, and independent means effective if said circuits are not established within a predetermined time interval to control said sender controlling means.
5. In a telephone system, a called line, selector switches for extending a connection to said line, a sender for controlling said switches, a plurality of control circuits extending between said switches, a pair of relays in one of said switches, one of said relays controlled by said sender to control the selecting functions of a succeeding switch, means in said first switch for controlling said sender, said means controllable by the simultaneous operation of both said relays over said control circuits established by said second switch, and independent means effective if said circuits are not established within a predetermined time interval to control said sender controlling means.
6. In a telephone system, a called line, selector switches for extending a connection to said line, a sender for controlling said switches, a plurality of control circuits extending between said switches, a pair of relays in one of said switches, one of said relays controlled by said sender to control the selecting functions of a succeeding switch, means in said first switch to reverse the connection of said relay to said fundamental circuit to control said sender, means for rendering said reversing means effective controlled by the simultaneous operation of both said relays over said control circuits established by said second switch, and independent means effective if said circuits are not established within a predetermined time interval to render said reversing means effective.
7. In a telephone system, a called line, selector switches for extending a connection to said line, a sender for controlling said switches, a pair of relays in one of said switches, a sequence switch associated with said switch, a fundamental circuit connecting said sender with one of said relays, means for operating said relay to control the selecting operations of said switch, means under the control of said relay to operate said sequence switch following each of said selecting operations, means for operating said relay to control the selecting operations of a succeeding switch, and means for again operating said sequence switch operating means only after all of the selecting functions of said succeeding switch have been completed.
8. In a telephone system, a called line, selector switches for extending a connection to said line, a sender for controlling said switches, a pair of relays in one of said switches, a sequence switch associated with said switch, a fundamental circuit connecting said sender with one of said relays, means for operating said relay to control the selecting operations of said switch, means under the control of said relay to operate said sequence switch following each of said selecting operations, means for operating said relay to control the selecting operations of a succeeding switch, and means for again operating said sequence switch operating means only after all of the selecting functions of said succeeding switch have been completed, said means comprising separate circuits for said relay and said sequence switch operating means simultaneously established by said succeeding switch.

In witness whereof, I hereunto subscribe my name this 26th day of August, A. D., 1926.

CLARENCE H. BERRY.
